Franklin D. Wallace

BY

Arthur M. Hood
ATTORNEY.

UNITED STATES PATENT OFFICE.

FRANKLIN D. WALLACE, OF WHEATLAND, INDIANA.

BURGLAR OR FIRE ALARM.

SPECIFICATION forming part of Letters Patent No. 655,427, dated August 7, 1900.

Application filed October 20, 1899. Serial No. 734,178. (No model.)

To all whom it may concern:

Be it known that I, FRANKLIN D. WALLACE,
a citizen of the United States, residing at
Wheatland, in the county of Knox and State
5 of Indiana, have invented a new and useful
Burglar or Fire Alarm, of which the follow-
ing is a specification.

My invention relates to an improvement in burglar or fire alarms.

10 The object of my invention is to produce a
cheap, compact, and efficient device which
may be used either as a burglar-alarm or
which may be used as a fire-alarm, the same
being of such form that when used as a fire-
15 alarm it may be sunk into the walls or ceil-
ings and be very inconspicuous.

The accompanying drawings illustrate my invention.

Figure 1 is a perspective view showing my device in position for use as a burglar-alarm. Fig. 2 is a section view thereof. Fig. 3 is a front elevation of the device when arranged as a fire-alarm. Fig. 4 is a central vertical section thereof.

25 In the drawings, 5 indicates a small open-ended casing, the open end of which is closed by a suitable cover 6, said cover being preferably of thin sheet metal which may be stamped into proper form. Cover 6 is provided with an opening 7, which is formed by throwing down toward the underside a tongue 8 and throwing up toward the upper side a pair of perforated ears 9 9. Mounted within casing 5 and longitudinally movable therein

30

35 is a terminal 10, the stem of which passes through a slot 8', formed in the free end of tongue 8. Terminal 10 is provided opposite opening 7 with a head 11, having upon its under side a beveled surface 12. Head 11 is

40 under side a beveled surface 12. Head 11 is provided upon its outer face with an opening, in which may be removably secured a pin 13, which pin is adapted to engage a cross-bar 14, which may be removably mounted in and between the perforated ears 9. Pin 13 on bar

45 between the perforated ears 9. Pin 15 or bar 14, or both, should be formed of easily-fusible material. Terminal 10 may be of sufficient weight to normally drop against terminal 15, which projects into one end of the casting 5, or a suitable spring 16 may be provided

ing 3, or a suitable spring 16 may be provided for that purpose. Secured to the terminal 10 and passing through a slot 17, formed in the side of the casing, is one wire 18 of a suit-

able electric circuit, and secured to terminal 15 is the other wire 19 of said circuit.

For use as a burglar door-alarm I provide a coöperating finger 20, which may be secured to the hinge edge of a door. The outer end of the finger 20 is beveled, so as to coöperate with face 12 of head 11 of terminal 10, as shown in Fig. 2. 55

The article of manufacture described may be used either as a fire or burglar alarm. If it is to be used as a burglar-alarm, casing 5 is sunk into the hinge side of the door-casing, with plate 6 lying flush therewith and wires 18 and 19 leading away therefrom behind the casing. Ears 9 are bent down flat, as shown in Fig. 1, and finger 20 is secured to the hinge edge of the door in such position that when the door is closed its beveled end will engage 70 the beveled face 12 of terminal 10 and raise said terminal or force it against the action of spring 16 away from terminal 15; but as soon as the door is partially opened terminal 10 will by the withdrawal of the finger 20 be released and allowed to again come into contact with the terminal 15. When the device is to be used as a fire-alarm, ears 9 are bent out, as shown in Figs. 3 and 4, pin 13 inserted in head 11, and bar 14 inserted in ears 9 beneath said pin 13, either or both of said parts to be made of easily-fusible material. Upon an increase of temperature beyond any desired point these fusible portions will break down, and thus allow the terminal 10 to come 85 into contact with terminal 15.

In the drawings I have shown the device arranged for open-circuit work; but it will be readily understood that by a mere reversion of parts—as, for instance, the shifting of terminal 15 to the opposite end of terminal 10—the device may be made available for closed-circuit work. 90

I claim as my invention—

1. As an article of manufacture, a casing, 95
a movable terminal mounted therein, a coöper-
ating terminal carried by said casing, a head
carried by said movable terminal, said head
being adapted to be acted upon and moved
with relation to the coöperating terminal by 100
means of a finger forced into engagement
therewith, and means carried by said casing
for supporting a fusible bar in position to en-
gage a portion of said head.

2. As an article of manufacture, a casing 5, a cover 6 therefor having an opening leading into said casing, a pair of perforated ears adjacent said opening, a movable terminal 5 mounted in said casing, a coöperating terminal, and means carried by said movable terminal for receiving a removable pin, the arrangement being such that said pin may be engaged by a fusible bar carried by said ears 10 and thereby normally held either out of or in engagement with the coöperating terminal.
3. As an article of manufacture, a casing 5, a cover 6 therefor having an opening 7 lead-

ing into said casing, a pair of ears formed integral with said cover adjacent said opening, 15 a sliding terminal mounted in said casing, a beveled head carried by said movable terminal opposite said opening, a coöperating terminal carried by said casing, and means carried by said sliding terminal for receiving a removable pin in position to be supported by a fusible bar supported by said ears. 20

FRANKLIN D. WALLACE.
